(57) **CLAIM**

The ornamental design for a flying avian, as shown and described herein.

DESCRIPTION

FIG. 1. Is a bottom plan of my flying avian;

FIG. 2. Is a top plan view thereof;

FIG. 3. Is a left side elevational view thereof with the right side elevational view being a mirror image thereof;

FIG. 4. Is a rear elevational view thereof; and,

FIG. 5. is a front elevational view thereof.

The portions shown in broken lines in FIG. 3 are for illustrative purposes only and form no part of the claimed design.
